poration of New York

Application May 6, 1948, Serial No. 146,201

Term of patent 14 years

(Cl. D3—26)

To all whom it may concern:

Be it known that I, Justin I. Kingson, a citizen of the United States, residing at New York, in the county and State of New York, have invented a new, original, and ornamental Design for a Child's Bib, of which the following is a specification, reference being had to the accompanying drawing, forming a part thereof.

Figure 1 is a front view of the child's bib, embodying my new design and Figures 2 and 3 are, respectively, side and back views thereof.

I claim:

The ornamental design for a child's bib, as shown.

JUSTIN I. KINGSON.
